UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR A SUPPORTING ARM FOR LIGHTING FIXTURES.

Application filed April 20, 1922. Serial No. 1,886. Term of patent 7 years.

To all whom it may concern:

Be it known that I, FRANK S. CROWELL, a citizen of the United States, and residing at Toledo, in the county of Lucas and State of Ohio, have invented a new, original, and ornamental Design for a Supporting Arm for Lighting Fixtures, of which the following is a specification, reference being had to

the accompanying drawing, forming part thereof.

Fig. 1 is a side view of a supporting arm for lighting fixtures, showing my new design.

Fig. 2 is a front view of the same.

I claim the ornamental design for a supporting arm for lighting fixtures, as shown.

FRANK S. CROWELL.
